(57) **CLAIM**

The ornamental design for a pneumatic tire, as shown and described.

DESCRIPTION

FIG. 1 is a front elevational view of a pneumatic tire showing our new design, it is being understood that the tire pattern repeats circumferentially throughout the outer circumference;

FIG. 2 is a perspective view of one side of the pneumatic tire shown in FIG. 1; and,

FIG. 3 is a side elevational view of one side of the pneumatic tire shown in FIG. 1, the opposite side being of identical appearance.

1 Claim, 3 Drawing Sheets

FIG. 1

FIG. 2

FIG. 3
